UNITED STATES PATENT OFFICE.

HERMINE GUIDEZ, OF NEW YORK, N. Y.

DESIGN FOR A PATTERN FOR DRESS-SKIRTS.

SPECIFICATION forming part of Design No. 35,847, dated April 1, 1902.

Application filed February 26, 1902. Serial No. 95,828. Term of patent 3½ years.

To all whom it may concern:

Be it known that I, HERMINE GUIDEZ, a citizen of the United States, residing in New York, borough of Manhattan, and State of New York, have invented and produced a new and original Design for Patterns for Dress-Skirts, of which the following is a specification, reference being had to the accompanying drawings, forming a part thereof, in which—

10 Figure 1 is a side elevation of a dress-skirt pattern, showing my new design; and Fig. 2 is a horizontal section of the same on line 2 2, Fig. 1.

As shown in the drawings, the body *a* of the 15 pattern is provided at its lower part with flounces *b*, which extend around the bottom of the skirt. Along the girdle-piece *a'*, transversely over the body *a*, and along the upper ends of the flounces *b* extend garland-like

ornaments *d*, which slant in downward direction at their rear ends *d'*. The ornaments *d* are formed of undulating stems and leaves, which divide the skirt into several sections, which increase in size from the girdle-piece to the flounces.

Having described my invention, what I claim as new, and desire to secure by Letters Patent, is—

25 The design for a pattern for dress-skirts, as herein shown and described.

30 In testimony that I claim the foregoing as my invention I have signed my name in presence of two subscribing witnesses.

HERMINE GUIDEZ.

Witnesses:

PAUL GOEPEL,
HENRY SUHRBIER.
